TUNING AND INDICATING APPARATUS FOR
RADIO RECEIVERS

Louis J. Wronke, Chicago, Ill., assignor to Belmont Radio Corporation, Chicago, Ill., a corporation of Illinois

Application June 29, 1936, Serial No. 87,892

10 Claims. (Cl. 116—124.1)

This invention relates to dial apparatus especially suitable for radio receiving sets, together with a mounting for such apparatus.

It is an object of the present invention to provide a more economical and satisfactory support and housing for the dial and dial apparatus than has heretofore been known. This is accomplished by using a single piece of metal drawn to shape as a complete support and housing. The drawn member also serves as a reflector and mounting for the dial lights to illuminate the dial.

Another object of the invention is to provide a simplified form of indicator for indicating some fact other than that indicated by the main dial, such as the wave band on which the set is operated. This is accomplished by providing a perforated disc rotated by the band control switch to illuminate different slots in the dial.

A further object of the invention is to provide a dial having independent calibrations for short wave reception and broadcast reception, together with means for indicating which of said bands the set is adjusted to receive, the calibrations and the wave band indicator being so correlated as to facilitate choosing the proper scale of calibrations in reading the dial. Thus, in the illustrated form the slot indicator for each frequency band is aligned with the calibrations for that band.

Another object of the invention is to provide with little additional cost a micrometer indicator for indicating the position of the condensers more accurately than is possible with the main hand on the ordinary dial. According to the present invention such a micrometer indicator is mounted on the pinion driving the gear segment connected to the main needle.

An additional object of the invention is to provide a simplified combination of condenser frame and control mechanism mounting with a corresponding reduction in cost of production.

Another object of the invention is to decrease the current consumption of radio receiving sets; first, by providing a housing for the dial apparatus of such nature that it is a good reflector so that adequate dial illumination may be obtained by a single lamp even though the dial is relatively large; and second, by providing means for automatically turning the dial light off, except during tuning. This last named feature is accomplished by normally open contacts closed by the tuning knob of the receiver so that the dial may be illuminated very easily whenever desired. The saving of current drain due to the dial light is, of course, especially valuable when

the set is being operated by a storage battery, as in automobile receiving sets, when excessive current consumption may cause great inconvenience.

Additional objects and advantages of my invention will be apparent from the following description, taken with the drawings, in which:

Fig. 1 is a front view of the dial assembly.

Fig. 2 is a side view of the same, showing its connection to the condenser frame.

Fig. 3 is a bottom view of the same with a portion broken away.

Fig. 4 is a sectional view of the same, taken substantially along the line 4—4 of Fig. 2.

Fig. 5 is a fragmentary sectional view, showing the mounting of the micrometer indicator 15 and driving pinion.

Fig. 6 is a front view of the mounting bracket for the mechanism illustrated in Fig. 5.

Fig. 7 is a view similar to Fig. 1, but showing a different dial with a different light arrangement.

Fig. 8 is a fragmentary cross-section taken substantially along the line 8—8 of Fig. 7, but also indicating an escutcheon plate, the latter being shown in a central cross-section.

Fig. 9 is a vertical longitudinal sectional view of a modified form of the invention in which the housing and condenser frame are combined.

Figs. 10 and 11 are fragmentary sectional views taken substantially along the line 10—10 of Fig. 7, showing two forms of dial light switches.

Fig. 12 is a fragmentary side view, partly in section, of a modification of the structure of Fig. 5.

Although this invention may take numerous forms, only a few have been chosen for the purpose of illustration. In all of these forms the dial and part of the apparatus are supported by a drawn metal support housing 11, which includes a cupped portion 12 secured to the tuning condenser frame of the receiving set. In the form shown in Fig. 1 it is secured to the end plate 13 of the condenser frame. Covering the front side of the cupped portion 12 is a dial 16, preferably of translucent nature and inscribed with suitable wave length or frequency marking which are suitably illuminated. In Fig. 4 the dial is illuminated from the back by two lamps 15 reflecting their light off of the sides and rear of the housing. As a matter of fact the housing 11 is such a good reflector that a single lamp may be used if the drive mechanism is not so positioned as to obstruct the light unduly. A needle or pointer 17 is carried by the condenser shaft 18, on which is also mounted a split gear segment 19, 55

which drives the condenser shaft 18 and the needle 17 without back-lash. The gear segment 19 meshes with and is driven by a pinion 21 carried by a shaft 20 which also drives a micrometer indicator 22 at the front of the dial. Pinion 21 is driven by pulley 23, belt 24, and pulley 26, which is mounted on shaft 27 adapted to carry the main control knob.

A modification of the mounting structure for 10 the pulley and micrometer indicator drive is illustrated in Fig. 12. This includes the pulley 23 mounted on a bearing shaft 200, carrying a spur gear 201. A brass bearing plate 202 is secured to the end plate 13 of the gang condenser, and has 15 a tapered hole 203 centrally thereof to support the tapered end of the shaft 202. A substantially U-shaped bracket 268 with both legs secured to the bearing plate and end plate supports the entire assembly.

20 The dial 16 is printed in reverse with an opaque ink with the indicia left clear so that the indicia are illuminated on a dark background. For simplicity of illustration, the black and white parts of the dial have been reversed within the line 28 25 in the drawings, so it should be understood that the entire face of the dial within that line is black except for the figures and lines which have been shown black, which on the actual dial are left white. The part of the dial outside of the 30 line 28 will of course be hidden by an escutcheon plate or other shield. Within the escutcheon the indicia will be illuminated from behind by the lamps 15.

A second control knob may be mounted on a 35 shaft 31, which may operate a switch 30 for shifting the receiving apparatus from one frequency band, as the broadcast frequency band, to another frequency band such as the short wave band. A wave band indicator disc 33 is rotatably mounted on the housing 12 by a rivet 35 holding the disc in engagement with a tension washer (not shown), and said disc is connected to the shaft 31 to be rotated by it. This connection is accomplished by means of a crank 36 40 (Fig. 4) rigidly secured to the shaft 31, and a link 37 pivotally secured at one end to the crank and at the other end to the disc 33. The link is secured to the disc at 37' off-center of said disc so that the crank-link mechanism is in 45 effect a bell-crank connection between the switch shaft and disc to place the openings 34 in the latter in the proper position for wave band indication as the wave switch is rotated. The plurality of slots 34 are covered by a translucent strip 34' and so positioned that for each wave band to which the receiving apparatus may be adjusted light shining through the slots 34 shines through one of the various slots 38 in the dial 16.

It will be observed that each of the wave band 50 indicating slots 38 is aligned with one of the three calibration lines 39. This makes it very easy for the user to know which of the three calibration lines he should read, since he reads the one aligned with the illuminated slot 38. The knowledge of which calibration line to read is made 55 still more clear by the arrangement of colors on the back of the dial. Thus, a strip 41 of one color such as green is applied behind the inner short wave line of calibration 39 and a strip 42 60 of another color such as red is applied behind the middle calibration line 39. A green strip or a strip of a third color may be applied behind the outer or broadcast calibration line, or, as illustrated, it may be left white. The colored 65 strips 41 and 42 may be bands of translucent

paint or a separately formed strip of translucent material. They may be applied by a printing process, or they may be sprayed or brushed on through stencils. The inner zone of color 43 is merely decorative. Since the dial is illuminated 5 from behind by lamps 15, the color on the back will be imparted to the lines as seen from the front, and the light is prevented from shining through the dial except along the desired lines and to show the desired indicia by the opaque 10 ink printed on the face of the dial as previously mentioned.

Although a single strip 34' has been illustrated as covering all three slots 34, it should be obvious that they may each be covered with a translucent strip corresponding in color to the color of the particular calibration strip 39 which it designates. Even without this, however, the fact that the three calibration lines are differently colored makes them very easily followed, and the 20 user very soon becomes so accustomed to the dial that without any conscious effort he reads the right line of calibration as indicated by the particular slot 38 which is illuminated.

The general construction of the apparatus will 25 be sufficiently clear in view of the foregoing rather general description, but a few of the details may also be described in case they may not be self-evident from the drawings. It should be recognized, however, that each of the novel features can be used with variations as to the other features. For example, various types of drive mechanism may be used in place of that shown.

As has been stated, the support housing 11 is a 35 single piece of metal drawn to the desired shape. If it is to be attached to plate 13 it is provided with three attachment bosses 51 pressed out from the bottom of the cupped portion 12. In Fig. 2 all three of these bosses are shown, while in Fig. 3 it may be understood that on the right side is seen 40 the boss shown at the middle of Fig. 2, while on the left side are both the bosses shown at the top and bottom in Fig. 2. These two bosses are in alignment so that only one shows. Screws 52 fitting in said bosses to rigidly fasten the housing 45 11 to the condenser frame 13 are shown in dotted lines in Fig. 1, to more clearly indicate the position of the three bosses, which positions are chosen so that these elements may be secured firmly together without any danger of applying 50 distortion strain to the condenser frame. The base of the triangle formed by the position of these three bosses is parallel to the plane of the condenser frame supports A and A' (Fig. 3) and the rotor plates of the condenser rotate out of 55 the stator plate toward this base line. Lock washers may be provided for the screws 52 as shown.

In many instances it will be preferred that end plate 13 be omitted, and a support housing 111 be 60 provided which is capable of serving the functions of the plate 13 as well as its other functions, as shown in Fig. 9. This is of course a more economical construction.

Support housing 11 may be punched to provide 65 any required openings, including the opening 56 in the bottom of the cupped portion 12, the opening 57 in the back of the cupped portion 12, the openings for the control shafts 27, 31, the openings for the lamps 15, as well as the numerous 70 small openings that are necessary for the attachment of parts. The belt 24 will extend downwardly through the opening 56, and the gear mechanism may be supported on the condenser frame and extend through the opening 57, al- 75

though, if preferred, the gear mechanism could be supported by the support housing 11. Although the gearing has been shown positioned within the housing in Fig. 3, it may be positioned 5 behind the end plate 13, or behind the housing 11 or the housing 111 as seen in Fig. 9.

If back-lash or play is present between the variable condenser and gear-mechanism driving the dial, which gear mechanism is actuated by a 10 control knob, it is impossible to get accurate readings on the dial, and it also affects the accuracy of the tuning control of the receiver. The construction of the split gear segment 19 is such as to eliminate this back-lash or play between it 15 and the pinion 21. The gear includes two segments side by side, one of which is keyed to the shaft 18 and the other of which is urged by a spring 61 toward a different angular position, with the result that the teeth of pinion 21 are 20 squeezed between the respective teeth and the two segments comprising the split segment 19.

Although this feature alone eliminates all back-lash between the indicating needle, the micrometer indicator, and the condenser, it is also desirable 25 that back-lash be eliminated between these members and the manually turned shaft 27. This is accomplished by providing a spring belt tightener including pulley 62 carried by an arm 63 forming an extension of a coil spring 64 carried 30 by a suitable peg 66, which may be secured to the support housing 11 in any suitable manner, as by a crimped split washer on the back of the housing. The tension on the arm 63 should be enough so that there will be no appreciable back- 35 lash in the belt 24, as the shaft 27 is turned in opposite directions. One advantage of the belt tightener is that it permits positioning the shaft 27 at one side as seen in Fig. 7, when desired, while holding the belt away from the other working 40 parts.

As seen in Fig. 5, the shaft 20 carrying pinion 21, pulley 23, and micrometer indicator 22 is preferably journaled in a bracket 68, which may desirably be a U-shaped bracket so as to support 45 the rotating structure on opposite sides of the pinion 21. The bracket 68 may be secured by suitable screws 70 to the condenser frame 13 with intervening spacer posts 69 to hold it at the proper position. Of course, when the pinion 21 is on one 50 side of the housing 111 (or plate 13) and the pulley 23 on the other, the special bracket 68 may not be necessary, especially if a bushing 75 is secured to the housing 111 for journaling the shaft on which the pinion 21 is carried.

55 The micrometer indicator 22 is preferably in the form of a translucent disc secured to the shaft 20 coated with an opaque substance except along the arrow line indicated. This disc projects through a suitable hole in the dial 16. To prevent 60 leakage of light between the disc 22 and the dial 16, the disc may be provided with an outwardly extending flange 83 which overlaps the sides of the hole formed in the dial.

The lamps 15 may conveniently be mounted in 65 sockets 71, which are supported by the housing support 11 by means of being inserted through rubber grommets 72. This avoids any electrical connection between the dial light and the condenser frame. When edge illumination is to be 70 provided, as in Figs. 7 and 8, the lamps will be positioned with their filaments in alignment with the glass 116 as there shown. It has been found, in the commercial embodiment of the invention, that the edge illumination from the top will carry 75 over the entire dial, but if the size or nature of

the dial is such that additional illumination is desired, a lamp 122 may be mounted at the top and in the center as shown in Fig. 8.

It has long been recognized that dial lamps consume an undesirable amount of current, especially in an automobile when there may be trouble in keeping the battery sufficiently charged. It has been the custom in the past to have the dial lamps lit whenever the set is operating. However, the only time when the lamps 10 are needed is when the set is being tuned, and, therefore, the present invention contemplates a convenient means for having the lights lit whenever illumination of the dial is desired for tuning and having them turned off at all other times. 15 As seen in Figs. 1 and 7, a pair of contacts 86 are positioned near the tuning shaft 27. The arrangement of these contacts 86 and the associated parts is seen best in Figs. 10 and 11, in which two modifications of the associated parts are shown. 20

In Fig. 10 it is seen that the shaft 27 is carried by a bushing 87 secured to the housing 11 in any suitable manner, as by being peened over in the hole therethrough, as shown. This shaft 27 may be slidably journaled in the bushing 87 or not, 25 as preferred. In Fig. 10 the control knob 88 is provided with a tubular sleeve 89 fitting over the shaft 27 and slidably thereon, with sliding movement being limited by a pin 90. The sleeve 89 bears against an insulating button 92 slideable 30 on the shaft 27. The button 92 carries a contact disc 93, which is adapted to engage the contacts 86. The contact washer 93 is urged outwardly by a spring washer 94, which may be insulated from the contact washer 93 by an insulating 35 washer 96. It is thus seen that when the knob 88 is pressed, the contact washer 93 engages the contacts 86 and completes the circuit to the dial lamp or lamps 15.

A similar, but somewhat simplified, arrangement is shown in Fig. 11, in which the structure is substantially the same except that the sleeve 89 is omitted. In this instance the entire shaft 27 slides in the bushing 87 in response to pressure on the knob 88 with the same result of 45 pressing the contact washer 93 against the contacts 86. The shaft 27 and the contact washer 93 are both pressed outwardly by the spring washer 94.

When this contact arrangement is used, it is 50 especially desirable that the depending portion of the housing 11 be adequately rigid. For this purpose it may be stiffened by ribs 80, preferably depressed in opposite directions to obtain the greatest stiffening effect. The entire front flange 55 of the support housing member is stiffened by a peripheral flange 81.

Some reference has already been made to the edge illumination features shown in Figs. 7 and 8. The principle of edge illumination is already 60 well known and need not be fully described. Preferably it may be stated that light from the lamps 115 passes into the edge of the glass dial 116, which bears suitable indicia. Except where it strikes these indicia, the light within the glass 65 is not noticeable. A black backing plate may be provided if desired, as if some translucent indicators such as the micrometer indicator 22 are to be used positioned adjacent holes in the backing plate 117.

The housing 11 lends itself admirably to the use of dial illumination, since the lamps may be mounted near the edge thereof, as shown in Fig. 8, and since the glass dial 116 may very easily be supported in the housing by providing 75

stamped out lugs 118 on which the glass may rest and by providing opening 119 in which clips 120 may be inserted, as seen best in Fig. 8.

The reference character 121 designates an es-
5 cutcheon plate for the dial and cabinet, Fig. 8, illustrating how the dial and dial lamp are posi-
tioned with respect to said plate.

From the foregoing it is seen that a dial-tuning assembly mechanism and mounting combination
10 is provided which at the same time is both eco-
nomical and extremely satisfactory. A single
drawn sheet metal member together with a con-
denser frame to which it is attached forms the
entire housing and support for the mechanism.
15 The mechanism is simple and inexpensive, and
yet is free from play or back-lash and includes
not only the main indicator needle but also a
micrometer indicator. Furthermore, this con-
struction provides for a main tuning indicator,
20 and vernier indication with two separate point-
ers, on separated shafts, and in its simplicity is
even less expensive than the single concentric
shaft construction heretofore employed in the
art. The present mechanism makes for more ac-
25 curate tuning than the prior structure. Al-
though the main indicator needle moves along
three lines of calibrations, the correct one to be
read is made obvious by an illuminated slot alined
therewith. The various lines of calibrations are
30 further distinguished by distinctive coloring. A
simple disc with a plurality of slots in it is the
means for selectively illuminating one of the slots.

Although the preferred form of my invention
has been herein shown and described, it is to be
35 understood that the invention is not limited
thereby, but is to be limited only by the prior
art. The following claims are intended to point
out some of the features now recognized as new,
rather than to limit the invention to these fea-
40 tures, except as may be required by the prior art.

I claim:

1. The combination of a radio tuning con-
denser having a condenser frame, a condenser
shaft rotatable with respect thereto for adjust-
45 ing the condenser, a housing support member
drawn from a single piece of sheet metal and in-
cluding a rearwardly cupped housing portion se-
cured to said condenser frame, and an extension
50 to one side of said cupped housing portion a
dial secured to said cupped housing portion, an
indicator movable with respect to said dial, and
mechanism for moving said indicator supported
entirely by the support structure including said
55 housing support member and extension and said
condenser frame, said mechanism including a
gear segment mounted on said condenser shaft
on which said indicator is also mounted, and a
pinion engaging said gear segment and carried
60 by a shaft spaced radially from said condenser
shaft and independent thereof, and a micrometer
indicator visible from in front of the dial oper-
ating over a micrometer scale and carried by said
pinion shaft.

2. A dial apparatus for a radio receiving set
65 adjustable to receive signals on a plurality of
bands of wave lengths with the same main dial
settings, including a dial and an indicator mov-
able with respect thereto, said dial having a plu-
rality of lines of calibrations along which said
70 indicator moves simultaneously, and means for
indicating which of said lines of calibrations
should be read for the particular adjustment of
the set, including a disc having a plurality of
windows therein, and means for moving said disc
75 in accordance with the adjustment of said re-

ceiving set, said dial also having a plurality of
windows therein so positioned that one of said
dial windows is alined with one of said disc win-
dows for each adjustment of the set.

3. A dial apparatus for a radio receiving set
adjustable to receive on a plurality of bands of
wave lengths with the same main dial settings,
including a dial and an indicator movable with
respect thereto, said dial having a plurality of
10 lines of calibrations along which said indicator
moves simultaneously, and means for indicating
which of said lines of calibrations should be read
for the particular adjustment of the set, includ-
ing a disc having a plurality of windows therein,
means for moving said disc in accordance with
15 the adjustment of said receiving set, said dial
also having a plurality of windows therein so
positioned that one of said dial windows is
alined with one of said disc windows for each ad-
justment of the set, each of said dial windows
20 being in alinement with the line of calibrations
corresponding thereto.

4. A dial apparatus for a radio receiving set
adjustable to receive on a plurality of bands of
wave lengths with the same main dial settings,
25 including a dial and an indicator movable with
respect thereto, said dial having a plurality of
lines of calibrations along which said indicator
moves simultaneously, and means for indicating
which of said lines of calibrations should be 30
read for the particular adjustment of the set, in-
cluding means for providing a visible indication
substantially in alinement with both ends of the
line to be read and intermediate said ends, and
means for imparting distinctive indicating colors
35 to said lines of calibrations.

5. The combination of a radio tuning mecha-
nism including a dial, a drawn metal support
housing for said dial, and a control knob mount-
ed thereon for both rotative and axial movement
40 and biased toward one axial position, a dial light
for illuminating said dial, and a switch for said
light closed by axial movement of said knob away
from its biased position; said switch including a
pair of contacts insulated from and supported by
45 said support housing, and a bridging contact op-
erated by said knob but insulated from said
housing.

6. Apparatus for controlling the tuning of a
radio receiver and indicating the tuned position
50 thereof, including a dial having a plurality of tun-
ing scales thereon, with each of said scales cor-
responding to a single wave band for radio recep-
tion and following a path closed over the greater
part of the length thereof and interrupted at one
55 point therein by a viewing space, an indicator mov-
able over said dial, tuning means for operating said
indicator, and a single member operating behind
said dial and providing an indication visible
through said viewing space to indicate which of
60 said scales is being utilized in the tuning of said
radio receiver.

7. Apparatus for controlling the tuning of a
radio receiver and indicating the tuned position
65 thereof, including a dial having a plurality of tun-
ing scales thereon, with each of said scales cor-
responding to a single wave band for radio re-
ception and following a path closed over the greater
part of the length thereof and interrupted at
70 one point by a viewing space, an indicator mov-
able over said dial, tuning means for operating said
indicator, an apertured member behind said
dial having a transparent colored material over
said aperture, a lamp mounted to project the
75 light therefrom through said aperture, with said

5 member movable to bring said aperture into alignment with a viewing space in the dial whereby the color of said material is visible through a viewing space in said dial to indicate the particular scale being utilized in the tuning of said radio receiver.

8. A multi-band radio receiver having a wave band change switch, a dial having a plurality of tuning scales thereon, lighting means to the rear 10 of the dial, a sight opening in the path of each tuning scale, an indicator member movable in back of said sight openings having a plurality of translucent portions therein corresponding in number to the number of tuning scales, and 15 means operable by said band change switch to move said indicator member to position a translucent portion behind a corresponding sight opening to permit light to shine through said portion and said opening to indicate the wave 20 band being utilized.
9. A compact tuning and indicating apparatus for a multi-wave band radio receiver including a tuning condenser, a dial plate with a plurality of tuning scales thereon, indicating means including an indicator movable over said scales, a 25 wave-band indicator movable to the rear of said

dial plate and rotatable control shafts having connecting means to both said indicators and condenser, and a one-piece frame for supporting said condenser, dial plate and indicating means with connected control shafts, said frame comprising a cupped housing with the condenser supported directly on the rear thereof, with said wave-band indicator movable therein behind the dial plate thereon, and an integral depending flange from said cupped portion for supporting 10 said control shafts.

10. Indicating apparatus for a multi-wave band radio receiver including a dial member having a plurality of tuning scales thereon, a plurality of viewing spaces on said member corresponding in number to the number of tuning scales, a disc rotatable behind said dial member having means to provide scale indication selectively visible at a viewing space, a control shaft spaced from said disc and eccentric connecting 15 means between said shaft and disc comprising a pair of pivoted arms with one arm rigidly secured to said shaft and the other arm pivoted to said disc at a point adjacent the outside edge thereof. 20
